UNITED STATES PATENT OFFICE

2,502,505

ADJUSTABLE SHOULDER PAD FOR
GARMENTS

Max Brief, San Francisco, Calif.

Application February 7, 1947, Serial No. 727,021

1 Claim. (Cl. 2—268)

1

My invention relates to garments or clothing and more particularly to an adjustable shoulder pad for garments, especially men's coats, and the like.

The purpose of the invention is to provide simple and novel means for lifting a shoulder portion of a coat or similar garment to enable a tailor to properly fit said portion of the garment to a person, one of whose shoulders may be higher than the other.

The adjustable shoulder pad of the present invention includes an adjusting device which embodies two pivoted sections, each having a convexly rounded inner side edge and a straight transverse inner end edge, while one section has a straight outer side edge at obtuse angles to its transverse inner end edge and a tapered outer end, and the other section has a straight outer side edge at acute angles to its straight transverse inner end edge and a tapered outer end, with calibrations or index markings along the outer side edge of said other section cooperating with the transverse inner end edge of the one section for indicating the degree of relative adjustment of the sections in raising a shoulder portion of a garment.

Other objects, advantages and features of invention may appear from the accompanying drawing, the subjoined detail description, and the appended claim.

Fig. 1 is a perspective view of a coat partly broken away to show the adjustable shoulder pad for lifting or raising the shoulder portion of a garment, and sewed between the outer cloth and the lining of the garment.

Fig. 2 is an enlarged cross sectional view of the construction shown in Figure 1, and

Fig. 3 is an elevation of the adjusting device forming part of the adjustable shoulder pad shown in Figure 1.

Referring to the drawings in detail, in which like reference characters refer to like parts throughout the several views, 5 designates a garment coat, 6 a shoulder portion of the coat, 7 a sleeve of the coat, and 8 a sleeve of a shirt worn under the coat. The present shoulder pad is disposed between the outer cloth 9 and inner lining 10 of the coat whose shoulder seam is indicated at 11. The shoulder pad includes inner and outer layers 12 and 13 of canvas between which is dis-

2

posed a padding 14 of cotton wadding or the like and an inner flannel layer 16, as is common in the tailoring art, especially in men's coats. The shoulder pad adjusting device 15 of the present invention is disposed between the padding 14 and the flannel layer 16, and the several parts are suitably stitched together as at 17.

The adjusting device 15 comprises two pivoted sections including a front section 18 and a rear or back section 19. Each of the sections 18 and 19 has a convexly rounded inner side edge 20 and a straight inner transverse edge 21, while the rear or back section 19 has a straight outer side edge 22 at obtuse angles to its transverse edge 21 and a tapered outer end 23. The sections 18 and 19 are substantially triangular in shape. The front section 18 has similar edges 20 and 21 and a substantially straight outer side edge 24 at acute angles to its straight edge 21, and has a tapered outer end 25 like the end 23. The edge 4 adjacent the edge 21 of section 18 is provided with graduations 26 cooperating with the edge 21 of the section 19. To permit this, the sections 18 and 19 are pivotally connected at their inner corners as indicated at 27 by a tubular rivet or the like so that one section swings relative to the other in overlapping relation at segments thereof as at 28 at their transverse edges 21 with their edges 22 and 24 in alignment when the device is arched as seen in Figs. 1 and 2, to raise the shoulder portion of the coat, or to lower the same. The sections 18 and 19 are produced or blanked out of flexible plastic, fibre, cardboard, or similar flexible sheet material which is relatively hard but sufficiently stiff to give support to the shoulder portion 6 of the coat and its padding, when stitched thereto. By this means, the shoulder portion of the garment may be adjusted, to give better form and for overcoming deformities as sloping or lopsided shoulders. When the sections 18 and 19 have been relatively adjusted as desired, they are stitched to the other members of the pad to secure them in adjusted relation.

45 Having thus described the invention, what is claimed as new is:

The combination with a coat having a shoulder pad, of an adjustment device to lift the shoulder comprising flexible sheet sections of substantially triangular form having rounded inner side

edges, and substantially straight transverse inner end and outer side edges, the inner corners of said sections being pivotally connected whereby said sections may be adjusted in overlapping relation and arched upwardly to raise a shoulder and its pad when secured thereto around the edges of the sections, and means at the inner portions of the sections to indicate the degree of raise imparted to the sections and shoulder.
